(57) **CLAIM**

The ornamental design for a spike for lawn sprinkler, as shown and described.

DESCRIPTION

FIG. 1 is a perspective view of the spike for lawn sprinkler in accordance with my invention;

FIG. 2 is a bottom elevation view thereof;

FIG. 3 is a top elevation view thereof;

FIG. 4 is a left side elevation view thereof;

FIG. 5 is a right side elevation view thereof;

FIG. 6 is a front plan view thereof; and,

FIG. 7 is a back plan view thereof.

The broken lines shown in FIGS. 1-7 are for illustrative purposes only and form no part of the claimed design.
